DESIGN FOR A RADIO CABINET OR THE LIKE

James Franklin Glover, Baltimore County, Md.,
assignor to Bendix Aviation Corporation, Tow-
son, Md., a corporation of Delaware

Application March 11, 1946, Serial No. 127,340

Term of patent 3½ years

(Cl. D56—4)

To all whom it may concern:

Be it known that I, James Franklin Glover, a citizen of the United States, residing in Maryland, in the county of Baltimore, have invented a new, original, and ornamental Design for a Radio Cabinet or the like, of which the following is a specification, reference being had to the accompanying drawings, forming a part thereof.

In the drawings:

Figure 1 is a front perspective view of a radio cabinet or the like, showing my new design;

Figure 2 is a top view thereof.

The characteristic features of my design reside in the portions shown by means of full lines in the drawing.

What is claimed is:

The ornamental design for a radio cabinet or the like, as shown and described.

JAMES FRANKLIN GLOVER.
